ATTORNEY

UNITED STATES PATENT OFFICE

WILLIAM A. HINES, OF WICHITA, KANSAS, ASSIGNOR, BY MESNE ASSIGNMENTS, TO THE STANDARD TRAFFIC MARKER COMPANY, OF WICHITA, KANSAS, A CORPORATION OF KANSAS

STREET STOP SIGNAL

Application filed November 20, 1926. Serial No. 149,584.

This invention relates to that class of signals used to indicate that a stop or retardation of speed of vehicles must be made at a road or street intersection.

5 Stop lines at street intersections, that is painted lines on the pavement of the street, ordinarily indicate to on coming drivers that a stop must be made before crossing the street. Traffic soon obliterates this line, so it becomes necessary to frequently repaint it.

10 My invention consists of a flexible sign or panel standing upright in the street to caution the on coming driver that he should come to a stop or at least decrease speed before crossing the street intersection. The panel is removably anchored in the ground so that when it becomes worn or deteriorates it can be taken up and a new panel immediately substituted without tearing up the street or 15 holding up traffic for any appreciable length of time while repairs are being made. I prefer to provide bending shoulders for the panel so that when the panel is bent over, the bent portion can lie against a curved shoulder support thereby limiting the liability of cracking the panel. I have, also, provided 20 clamping bars for the panel which can be secured to it as a part of the unitary structure, removably secured in an anchoring slot and 25 rigidly held against accidental displacement, by anchoring clamps. There are other novel 30 features of the invention which will be specifically referred to hereinafter, reference being had to the accompanying drawings in 35 which:—

Fig. 1 is a perspective view of the front end of a motor vehicle showing a front wheel in contact with the sign ready to tilt it.

Fig. 2 is a perspective view of the sign complete and

Fig. 3 is a cross-sectional view through the sign.

In carrying out my invention I provide a slot or trench 1 in the ground and at the respective ends of the trench I embed two transversally disposed anchor blocks 2 and 3. Each anchor block has a threaded opening 4 to receive a threaded end of an anchor bolt to be hereinafter referred to. The sides of the 45 trench or slot are slightly inclined. The

trench or slot receives the base consisting of clamping bars 5 and 6 which have serrated inner faces resembling corrugations 7 and 8 at their lower portions to constitute jaws to grip the panel 9 between them, the 55 base or clamping bars 5 and 6 and the panel 9 being secured together as a unitary structure by suitable fastening devices indicated as bolts. When the unitary structure is held together by the bolts, the base consisting of 60 the clamping bars 5 and 6 is wedge-shaped because the bars are thickest at their upper portions. That is, the sides of the base converge downwardly, consequently when the 65 unitary structure is dropped into the slot or trench it will tend to wedge therein, the wedging action being augmented by clamps consisting of clamping bars 11 and 12 and the 70 bolts 13 and 14 which pass through them with their threaded ends engaging the threaded portions 4 of the anchor blocks 2 and 3, the lengths of which are greater than the width of the slot or trench 1. The clamping bars 75 11 and 12 are, preferably, slightly countersunk in the upper edges of the clamping bars 5 and 6 as indicated at 15 and 16. These bars can readily bridge the gap between the clamping bars because the ends of the clamping bars extend beyond the ends of the panel 9.

In actual practice the sign panel 9 will be 80 of such width that the wheels of the vehicle may straddle it, but there will be times when careless driving will cause the wheels to ride over the panel. This would tend to crack the panel unless some means was provided to relieve the bending strain. Therefore, I have 85 provided the upper edges of the members 5 and 6, at their inner faces, with curved shoulder portions 17 and 18, the curves being generated on arcs equal to the normal curvature 90 of the bend of the panel when it is bent over. Therefore, the panel will bend against a rigid curved shoulder, to relieve strain. The base consists of the two bars 5 and 6, flared at its 95 top and forms a groove to catch dirt so that when the unitary structure is lifted from the slot or trench any accumulated dirt against the panel will come with it, leaving the trench clean so that the unitary sign structure can be inserted in the slot or trench. It is also to 100

be noted that any dirt accumulating in the slot will act as a cushion for the panel when the panel is bent over against the shoulder.

It is to be understood that the flexible sign panel 9 will ultimately wear out so that a new one must be substituted from time to time. This can be accomplished by loosening the bolts 13 and 14 and lifting the unitary sign structure from the slot. The panel may 10 consist of rubber reenforced by a fabric 19 and the panel is preferably tapered in cross-section so that the upper end 20 is narrower than the base. This is for the purpose of having the upper end of the panel lighter than the base so that it will tend to spring back to a vertical position after the wheel has passed over it.

Any appropriate indicia may be on either or both faces of the sign panel and any appropriate color may be employed for the panel.

In actual practice the unitary structure, consisting of the flexible panel and the two clamping bars, is first fastened to the base 25 members 2 and 3 by the clamping bars 11 and 12 and the bolts 13 and 14. The whole connected structure is then ready to be embedded in the street pavement, usually concrete.

30 The concrete or other material is caused to surround the base and the anchor blocks 2 and 3, the top edges of the side bars 5 and 6 being approximately in line with the surface of the street paving.

35 When it is desirable to replace a worn sign, it will only be necessary to remove the bolts 13 and 14 from engagement with the blocks 2 and 3, lift out the unitary structure and the clamps 11 and 12. Then a new unitary structure can be dropped into the trench or slot 1, formed by the first sign element and since its base will be like the base of the first sign element from which the slot 1 was formed, it will be apparent that it will fit 45 tight in the slot and that it can be rigidly held in the slot by the clamps. The time required to take out the worn sign and replace it with a new one will be so short that it will be practically unnecessary to hold up traffic to any appreciable extent while the change is being made. This is important because it will not be necessary to block off the street while making repairs to the signs.

50 What I claim and desire to secure by Letters Patent is:—

1. In combination, a grooved ground-engaging base having a flared groove in its upper longitudinal edge, and a panel of flexible material in the groove and spaced from the side thereof, ground embedded blocks, transverse clamping bars engaging the base and bolts securing the bars to the blocks.

60 2. As an article of manufacture, a stop sign unit comprising a flexible panel and clamp-

ing bars permanently attached to opposite sides of the lower edge of the panel.

3. As an article of manufacture, a stop sign unit comprising a flexible panel and clamping bars permanently attached to the 70 opposite sides of the lower edge of the panel, the outer faces of the bars being inclined so that when they are fastened to the panel they constitute a wedge.

4. As an article of manufacture, a stop sign unit comprising a flexible panel and clamping bars permanently attached to opposite sides of the lower edge of the panel, the inner faces of the upper portions of the bars having offset curved faces over which the 80 panel may bend.

5. In combination, a grooved ground engaging base having a flared groove at its upper longitudinal edge, said base comprising two spaced bars and a flexible panel permanently secured between the bars.

6. In combination, a ground engaging base, comprising spaced bars, a panel of flexible material permanently fastened between the bars, ground embedded blocks and means for 90 removably fastening the base to the blocks.

7. In combination, a grooved ground engaging base having a flared groove at its upper longitudinal edge, a panel of flexible material, means for fastening the panel in 95 the groove in spaced relation to the sides thereof, ground embedded blocks and bolts securing the base to the blocks.

8. In combination, a grooved ground engaging base having a flared groove at its 100 upper longitudinal edge, a panel of soft flexible material, and means for fastening the panel in the groove with the sides of the panel spaced from the sides thereof.

In testimony whereof I affix my signature. 105
